UNITED STATES PATENT OFFICE.

FRANK B. ACKERMANN, WILLIAM C. STEFFAN, AND WALTER J. GREINER, OF CHICAGO, ILLINOIS.

PENCIL.

Application filed September 7, 1923. Serial No. 661,491.

This invention relates to pencils, and more particularly to pencils of mechanical lead feeding type, and an object of the invention is to provide a magazine pencil structure in which the lead is fed through the point of the pencil by rotation of a cap at the butt of the pencil and one in which the lead feeding means is charged from the tip of the pencil.

Another object of the invention is to provide a mechanical pencil as specified in which the lead magazine is charged and empties out at the tip end of the pencil, and also to provide means in the pencil structure for securely holding the active lead feeding means in position.

The present invention is an improvement over our pencil structure disclosed in the application filed October 2, 1920, Serial No. 414,165, and the present improved construction embodies, besides the tip charging structure and tip opening out magazine, a simplified more rigid and more easily operated structure than that disclosed in the application above mentioned.

Other objects of the invention will appear in the following detailed description taken in connection with the accompanying drawings wherein:-

Fig. 1 is a side elevation of the improved pencil.

Fig. 2 is a longitudinal section through the pencil.

Fig. 3 is a view partly in side elevation, and partly in section of a part of the barrel of the pencil structure.

Fig. 4 is a detail view partly in side elevation, and partly in section of the lead feeding stem and feed screw.

Fig. 5 is an enlarged section through the cap or butt end of the pencil structure.

Fig. 6 is an enlarged section through the tip structure.

Fig. 7 is a cross section on the line 7—7 of Fig. 2.

Fig. 8 is a cross section on the line 8—8 of Fig. 2.

Fig. 9 is a cross section on the line 9—9 of Fig. 2.

Fig. 10 is a cross section on the line 10—10 of Fig. 2.

Referring more particularly to the drawings, the improved pencil comprises a casing 1, which is preferably constructed of an inner metal sleeve 2 and an outer decorative

sleeve 3 of hard rubber or analogous material as disclosed in our companion application filed August 20, 1921, Serial No. 493,884. The inner metal sleeve 2 has its butt end spun to provide an outwardly bulging transversely curved portion 4 which fits snugly in the concave inner surface of the annulus 5 which is formed on the sleeve 6, thereby connecting the sleeve 6 to the inner metal sleeve 2 for rotary movement but to prevent longitudinal movement of these sleeves. The sleeve 6 has its portion outwardly of the annulus 5 internally screw threaded as shown at 7 to receive the threaded plug 8, which is in turn rigidly connected by means of the up-set end 9 of the cylinder portion 10, to the eraser carrying sleeve 11. A decorative eraser enclosing cap 12 is removably mounted about the sleeve 11 and its inner end abuts the outer end of the sleeve 6 which projects beyond the perimeter of the carrying sleeve or cup 11.

The cylindrical portion 10 is formed as an integral part of a feeding sleeve 14 and this feeding sleeve 14 is threaded internally as at 15. These threads 15 cooperate with the screw 16 for feeding the lead propelling stem 17 longitudinally within the barrel 18 for forcing the lead out of the constricted tip 19 of the barrel 18 and through the tip 20 of the pencil structure.

The barrel 18 comprises a relatively large feeding sleeve receiving portion 21 and a reduced stem receiving portion 22 which terminates in the constricted tip 19. The feeding sleeve receiving portion 21 defines opposite diametrically longitudinally extending slits 23 and is formed to close these slits intermediate their end portions to provide firm frictional gripping engagement between the portion 21 and the sleeve 14 for resisting longitudinal withdrawal of the feeding sleeve 14 from the barrel 18. The reduced stem receiving portion 22 of the barrel 18 is provided with a flattened portion 25 which is adapted to engage the square portion of the stem 17 to hold the stem against rotation so that as the feeding sleeve 14 is rotated by rotation of the cap 12, cup 11 and coupling sleeve 6, the stem 17 will be moved longitudinally in the barrel 18 for forcing a length of lead as shown at 26 through the tips 19 and 20. It will be noted by particular reference to Fig. 3 of the drawings that the tip 19 is split longi-

tudinally as shown at 27 while the apex of the tip 20 is provided with a relatively short bore 28 of uniform diameter, through which the lead is fed, thereby providing a dual frictional grip on the lead, and also eliminating on the tip 20 any sharp edges which would engage the lead and which have a tendency to cause the lead to break easily during writing.

10 The barrel 18 has a coupling 30 either formed thereon or mounted thereon and welded, shrunk, or otherwise securely attached thereto. The coupling 30 comprises a portion 31 which is relatively large in 15 diameter and which is threaded as shown at 32 for threading into the lower threaded end 33 of the inner casing sleeve 2. A portion 34 which is smaller in diameter than the portion 31 is connected to the portion 20 31 by the intermediate portion 35 of the coupler, the outer perimeter of which tapers as clearly shown in Fig. 6.

It will be noted, by particular reference to Figs. 3 and 10 of the drawings that the 25 coupling 30 is slotted, longitudinally at diametrically spaced points as shown at 36 to provide space to permit the passing of leads into the magazine space 37 within the casing sleeve 2 and about the barrel 18 thereby 30 permitting the charging or discharging of the magazine of the pencil from the tip thereof. The longitudinally extending slots 36, are of sufficient width and depth so as to permit two or more leads to be placed or 35 withdrawn from the magazine through each slot. To charge or discharge the magazine the substantially conical tip 20 must be disconnected from the coupling 30, however it is unnecessary to disconnect the coupling 40 for charging the barrel 18. The substantially conical tip 20 has an annulus 38 formed integrally therewith a short distance inwardly of its base or enlarged end and the annulus 38 is provided with a threaded bore 45 39 which cooperates with the reduced portion 34 of the coupling 30 to detachably connect the tip 20 to the casing of the pencil through the medium of the coupling 30. The edge 40 at the base or enlarged end of the tip 20 is beveled as clearly shown in 50 Figs. 2 and 6 of the drawings and fits snugly against the adjacent beveled end 41 of the outer sleeve 3 of the pencil casing.

The plug 8 is threaded so that it may be 55 attached to the coupling 6 during the assembling of the pencil structure. However, owing to the particular construction of the pencil, and the fact that it is desired that the coupling sleeve and eraser cup rotate in 60 unison, for feeding the lead from the pencil a substantial permanent connection is provided between the plug 8 and sleeve 6 by placing glue, cement or other suitable adhesive on the threads of the plug 8 when 65 it is threaded into the sleeve, which adhesive

material when dried forms a substantial inseparable connection between the plug 8 and the eraser cup carried thereby and the coupling sleeve 6.

As shown in Fig. 1 of the drawings the 70 outer surface of the annulus 5 may be knurled or roughened so that the feeding sleeve 14 may be rotated either by gripping the eraser cap 12 or by gripping the coupling sleeve 6 and rotating it. 75

The operation of the pencil is as follows: When first charging the pencil, the tip 20 is removed to permit the withdrawal of a length of lead from the magazine 37, which length of lead is forced, from the tip 19 into 80 the constricted portion 22 of the barrel 18, after which the tip 20 is replaced, by threading the portion 34 of the coupling into the annulus 38. The cap 12 is then rotated, which in turn rotates the coupling sleeve 85 6 and plug 8 rotating the feeding sleeve 14. The feeding stem 17 is held against rotation by its engagement with the flattened portion 25 which causes movement of the stem 17 longitudinally in the barrel 18 90 and feeds the lead 26 into writing position through the tip 20.

It is, of course, to be understood that the invention may be constructed in other manners and the parts associated in different 95 relations and, therefore, we do not desire to be limited in any manner except as set forth in the claims hereunto appended.

Having thus described our invention what we claim is:— 100

1. In a pencil, a casing comprising an inner sleeve, a coupling sleeve provided with an annulus having an inner concave surface, said inner sleeve extending into said coupling sleeve and having its end spun outwardly into said annulus for connecting said sleeves for relative rotary movement, a plug carried by said coupling sleeve, an eraser cup rigidly connected to said plug and adapted for rotation synchronously with said coupling sleeve, and lead feeding means adapted to be operated by rotation of the coupling sleeve, a lead guiding barrel within said inner sleeve, a coupling carried by said barrel, a tip detachably connected to said coupling, said coupling being detachably connected to said inner sleeve. 110

2. In combination a sleeve threaded internally at its lower end, a feeding sleeve including a coupling member at its lower end and threaded externally at its upper end portion for threaded engagement with the internal threads of the sleeve and including a reduced thread bearing end portion, means operable by the feeding sleeve for feeding a length of pencil lead through the feeding sleeve, and a tip having an internally threaded portion adapted for threaded engagement with the reduced end portion of the coupling member. 120 125 130

3. In a pencil, a barrel, a coupling carried by said barrel, a substantially conical tip, an annulus formed interiorly of said tip and being internally threaded, said coupling having a threaded portion for engagement in said annulus to connect the tip and coupling, a casing about said barrel, said casing comprising inner and outer sleeves, said inner sleeve provided with a threaded portion, and 10 a threaded portion on said coupling for connecting the coupling and casing, said coupling being slotted longitudinally at diametrically opposed points, the slots being of sufficient width and depth to permit a plurality of leads to be passed through each slot to permit charging or discharging of the leads from the interior of the casing about 15 said barrel.

4. In a pencil, a casing comprising an inner sleeve, a coupling sleeve provided with an annulus having an inner concave surface, said inner sleeve extending into said coupling sleeve and having its end spun out 20

wardly into said annulus for connecting said sleeves for relative rotary movement, a plug 25 carried by said coupling sleeve, an eraser cup rigidly connected to said plug and adapted for rotation synchronously with said coupling sleeve, and lead feeding means adapted to be operated by rotation of the 30 coupling sleeve, a lead guiding barrel within said inner sleeve, a coupling carried by said barrel, a tip detachably connected to said coupling, said coupling being detachably connected to said inner sleeve, said barrel 35 provided with a relatively large portion being split longitudinally and flattened at said split portion to increase frictional engagement between the barrel and lead feeding means. 40

In testimony whereof we affix our signatures.
